REFRIGERATING APPARATUS

Leslie B. M. Buchanan, Springfield, Mass., assignor to Westinghouse Electric & Manufacturing Company, East Pittsburgh, Pa., a corporation of Pennsylvania

Application October 1, 1936, Serial No. 103,507

8 Claims. (Cl. 62—4)

My invention relates to refrigeration apparatus, more particularly apparatus for maintaining first and second zones of a refrigerator at different temperatures, and it has for an object 5 to provide improved apparatus of this kind.

It has been suggested, heretofore, to provide a common refrigerant condensing unit for circulating refrigerant through the evaporator elements of relatively high and low temperature chambers 10 of a two-temperature refrigerator and to increase and decrease the cooling effect of one of the evaporators as the heat load impressed thereon increases and decreases. If the heat load on one or both evaporators increases beyond a predetermined value, difficulty is experienced in depressing 15 the temperature of the evaporator elements when a condensing unit having sufficient capacity to refrigerate the elements normally, but insufficient to depress their temperature when the heat load increases beyond said predetermined or abnormal value, is employed.

In accordance with my invention, the load impressed on the condensing unit by one of the evaporators is substantially reduced or terminated 25 until the temperature of the evaporators is reduced to a value at which normal control may be restored.

Accordingly, it is an object of my invention to render one of the evaporators of a two-temperature refrigerator substantially ineffective for cooling when the heat load on the refrigerating mechanism is abnormally high.

The foregoing and other objects are effected by my invention as will be apparent from the following description and claims, taken in connection with the accompanying drawing, forming a part of this application, in which:

The single figure of the drawing shows diagrammatically, refrigerating apparatus arranged 40 in accordance with my invention.

Referring now to the drawing, I have shown my improved apparatus including a cabinet 10 having relatively low and high temperature chambers 11 and 12, respectively. An evaporator structure including first and second elements, 13 and 14, respectively, receives condensed refrigerant from a suitable condensing unit shown at 15. The evaporator elements 13 and 14 are disposed 45 for cooling media in the low and higher temperature chambers 11 and 12, respectively. The element 13 may be arranged for cooling the air in chamber 11 and for the freezing of fluids contained in receptacles 16. The element 14 may be 50 finned as shown, and functions to cool the air in

the compartment 12 which defines a storage space for perishables, such as, articles of food.

Included among the elements of the condensing unit 15 are compressor mechanism 17, driven by a motor 20, and a refrigerant condenser 18 5 that is preferably cooled by a fan 19. The latter fan is driven by a motor 21 having a winding 22. The winding of the motor 20 that actuates the compressor mechanism 17 is shown diagrammatically at 23 and may be connected in parallel with 10 the fan motor winding 22 so that both the mechanism 17 and the fan 19 are operated together.

The refrigerating system operates on the well known compressor - condenser - expander cycle wherein vaporous refrigerant is withdrawn from 15 the evaporator elements 13 and 14, through a conduit 24, by the compressor mechanism 17. The refrigerant gas is compressed to a relatively high temperature by the compressor 17 and is delivered to the condenser 18 wherein it is cooled 20 and condensed. The condensed refrigerant flows to a suitable expansion device 25, shown by way of example, as a high side float valve. The pressure of the refrigerant is reduced by the float 25 valve 25 and is conveyed to the evaporator portions 13 and 14 wherein it is vaporized for abstracting heat from the evaporator portions 13 and 14. This cycle of operation continues repeatedly during operation of the compressor mechanism 17.

During periods when the higher temperature chamber 12 requires cooling, forced circulation of the air therein is effected by a fan 27 preferably driven by a motor 28. The motor 28 receives energizing current from line conductors 35 L₁, L₂ which also provides the source of power for the motors 20 and 21.

In accordance with my invention, operation of the compressor mechanism 17 is controlled in accordance with the evaporator temperature. A 40 thermostat 31, preferably of the gas type, controls energization of the motor windings 22 and 23 and includes an expandible bellows 32 connected by a tube 33 to a bulb 34. The latter is preferably secured to the evaporator element 14 45 adjacent the portion thereof which is connected to the element 13. The reason for this arrangement will be referred to hereinafter.

As the operation of gas type thermostats is well known in the art, no detailed description of their operation is deemed necessary. Briefly stated, however, the bellows expands and contracts as the pressure therein increases and decreases, which pressure is a function of the temperature of the fluid in the bulb and bellows. The con- 50 55

tact 35 engages a stationary contact 38 in response to a predetermined high temperature of the evaporator structure and is disengaged from the contact 38 in response to a predetermined low temperature of the evaporator structure. One terminal of the compressor motor winding 23 is connected directly to line conductor L₁ and the other terminal is connected to contact 38 by a conductor 39. The movable contact 35 is connected to the line conductor L₂ as shown.

During normal operation of the apparatus, the motor winding 23 is energized as the contacts 35 and 38 are engaged due to a predetermined high temperature of the evaporators 13 and 14. Accordingly, refrigerant is circulated through the evaporators for abstracting heat therefrom. When the temperature is depressed to the desired value, the contacts 35 and 38 are disengaged for deenergizing the winding 23, whereupon the compressor mechanism 17 stops and refrigeration of the evaporators 13 and 14 is terminated.

A second stationary contact 41 engages the movable contact 35 continuously during the normal operation described heretofore and is disengaged therefrom during abnormal periods or periods when the temperature of the evaporators is above a predetermined value, higher than the value at which the contacts 35 and 38 first engage. The contact 41 is connected by a conductor 42 to one terminal of the fan motor 28, so that, the energizing circuit for the fan motor 28 is conditioned to operate the fan motor during normal operating periods or the periods when the contacts 41 and 35 are engaged. The other terminal of the fan motor 28 is connected to the line conductor L₁ by a conductor 43 controlled by a thermostat 44.

The thermostat 44 operates in response to the temperature of the air in the chamber 12 in such manner that it energizes and deenergizes the fan motor 28 when the temperature of the air attains predetermined high and low values. Forced circulation of air in the compartment 12 is, therefore, effected in the chamber 12 during periods when it is calling for cooling and, during periods when it is satisfied, forced circulation ceases.

The position of the apparatus as shown in the drawing indicates that cooling is not required by either chamber 11 or 12. Both thermostats 31 and 44 are in their open positions and neither air nor refrigerant is circulated. Some limited circulation of air in chamber 12 may be induced thermally but it is ineffective to reduce the temperature of the body of air in the chamber 12, as the transfer of heat between the air and the evaporator 14 is at a relatively low rate.

The temperature of the evaporators 13 and 14 is maintained between predetermined temperatures such as, for example, 5 to 15° F., by the thermostat 31, and the thermostat 44 may be adjusted to maintain the air in the chamber 12 between 40° and 45° F. The evaporator 14 is so proportioned that with a temperature differential of between 25° to 40° F. prevailing between the evaporator 14 and the air, cooling of the body of air in the chamber 12 is not effected except during periods of forced circulation when the rate of heat transfer is high.

Operation

Assume that the thermostat 44 is satisfied and the circuit of the fan 28 is open. Assume further that the temperature of the evaporators 13 and 14 rises to 15° in the example previously cited, the thermostat 31 effects engagement of contacts 35

and 38 for initiating operation of the condensing unit 15. Refrigerant is vaporized in both evaporators, but mainly in the evaporator 13 due to the low rate of heat transfer between the air 12 and evaporator 14. Heat is abstracted from the evaporator 13 and media cooled thereby until the temperature of the evaporators has been depressed to 5° F., at which temperature the thermostat 31 becomes satisfied and opens contacts 35 and 38. Circulation of refrigerant by the condensing unit 15 is, therefore, terminated.

Closure of the contacts of the thermostat 44, due to a rise in temperature of the air in the chamber 12, effects energization of the motor 28 and circulation of air by the fan 27. Accordingly, the transfer of heat from the air to the evaporator is effected at a high rate and the temperature of the air is depressed. The temperature of the evaporator 14 rises at this time and, as the temperature thereof rises to 15°, the thermostat 31 operates to start operation of the condensing unit 15.

The bulb 34 is preferably located where it will quickly reflect temperature rises in the evaporator 14 due to circulation of air. As shown, it is connected to a portion 14a of the evaporator adjacent to the portion 13 and just outside of the colder compartment 11, at which location temperature variations in either portion 13 or 14 are quickly reflected. At this location the bulb 34 is contacted by the circulated air and its temperature is therefore affected by the relatively warm air circulated by the fan, as well as by the temperature of the evaporators. With this arrangement, the thermostat 31 may operate in an anticipating manner to start the condensing unit 15 when the relatively warm air is circulated in contact with its bulb 34.

The foregoing described operation of my improved apparatus may be termed normal operation during which the media in chambers 11 and 12 are maintained at temperatures within prescribed limits. There may be periods when it is difficult to quickly effect cooling of the evaporators 13 and 14, such as during an initial start when both chambers 11 and 12 are warm, or when an exceptionally high heat load prevails in the compartments 11 and 12. This condition may prevail unless a condensing unit having a capacity greatly in excess of the capacity necessary for normal operation is employed. During these periods, it is understood that the fan 27 is operating. In order that the temperatures of the evaporators 13 and 14 may be depressed in a relatively short space of time, I provide means including the contacts 35 and 41 for rendering the fan 27 inactive when the temperature of the evaporators is above a predetermined value of say 30° F. This may be termed an abnormally high temperature.

The bellows 32 of the thermostat 31 is expanded sufficiently to disengage contacts 35 and 41 when the temperature of the evaporators 13 and 14 is above 30° F., and therefore, the fan motor 28 is rendered incapable of operation regardless of the position of the thermostat 44. In this position, the contact 35 remains in engagement with contacts 38 so that the condensing unit 15 operates to circulate refrigerant.

The evaporators 13 and 14 are readily cooled due to the heat load on evaporator 14 being reduced. As the temperature of the evaporators 13 and 14 is depressed to 30° F., the contacts 35 and 41 engage for restoring normal control.

From the foregoing, it will be apparent that I

have provided improved two-temperature refrigerating apparatus wherein refrigeration of both zones may be effected selectively, with preference being given normally to one zone and, in the event 5 of an abnormal operating condition, preference is transferred to the other zone.

The form of refrigerant condensing unit employed in the disclosure is shown by way of example and it will be understood that other types 10 of condensing units may be employed in accordance with my invention. The thermostats disclosed are shown in their simplest form for the sake of clearness and it will be understood that certain refinements have been omitted, particularly, quick acting switch mechanisms.

While I have shown my invention in but one form, it will be obvious to those skilled in the art that it is not so limited, but is susceptible 20 of various changes and modifications without departing from the spirit thereof, and I desire, therefore, that only such limitations shall be placed thereupon as are imposed by the prior art or as are specifically set forth in the appended claims.

25 What I claim is:

1. In refrigerating apparatus, the combination of means defining first and second zones to be refrigerated, an evaporator structure disposed for cooling media in both zones, means for circulating refrigerant through the evaporator structure, means for effecting forced circulation of the air in one zone in heat transfer relation with the evaporator for cooling the air, and means responsive to a predetermined abnormally high 30 temperature of the evaporator structure for rendering the air circulating means incapable of operation.

2. In refrigerating apparatus, the combination of a cabinet structure having relatively high and 40 low temperature zones formed therein, an evaporator structure having portions disposed within both of said zones, means for circulating refrigerant through said evaporator for effecting cooling of the media in the zones, means responsive to the temperature of said evaporator for controlling the circulating means, a device for effecting forced circulation of the medium to be cooled in heat transfer relation with the evaporator portion in one of the zones, means responsive to 45 a predetermined temperature of the medium in said one zone for controlling the operation of the device, and means for rendering said device ineffective when the temperature of the evaporator increases to a predetermined value.

55 3. In refrigerating apparatus, the combination of means defining first and second zones to be refrigerated at different temperatures, an evaporator structure having first and second portions disposed for cooling the air in the zones, respectively, means for circulating refrigerant through the evaporator, a fan for translating the air in one of the zones in heat transfer relation with the evaporator portion therein, means responsive to the temperature of the air in said 60 one zone for controlling the operation of the fan, means responsive to the temperature of an intermediate portion of the evaporator for controlling the operation of said refrigerant circulating means, and means for terminating operation of said fan in response to an abnormally high 65 temperature of the evaporator.

4. In refrigerating apparatus, the combination of means defining first and second compartments to be refrigerated, an evaporator structure having first and second portions thereof disposed for

cooling the air in the first and second compartments, respectively, means for circulating refrigerant through the evaporator structure, said second evaporator portion being so proportioned that limited cooling of the air in the second compartment is effected by thermally induced air currents, means for translating air within the second compartment in heat transfer relation with the second evaporator portion whereby effective cooling of the air is obtained, means responsive to the temperature of the air in the second compartment for controlling the operation of the air translating means, and means responsive to the temperature of the evaporator for controlling the operation of the refrigerant circulating means, 15 said last-mentioned temperature responsive means being so disposed that it is affected by the air circulated by the air translating means.

5. In a refrigerating system, the combination of a cabinet having first and second chambers therein, first and second evaporator elements disposed in heat transfer relation with the air within said chambers, respectively, means for supplying condensed refrigerant to the evaporator elements for vaporization therein at substantially equal pressures, means for controlling said refrigerant supply means in accordance with the temperature of the evaporator elements, a fan for translating air in said second chamber in heat transfer relation with the evaporator element therein, a thermostat actuated by the temperature of the air in the second chamber for controlling the operation of the fan, and means responsive to an abnormally high temperature of the evaporator elements for rendering the fan inactive in 35 independently of the thermostat.

6. In a refrigerating system, the combination of a cabinet having first and second chambers therein, first and second evaporator elements disposed in heat transfer relation with the air within 40 said chambers, respectively, means for supplying condensed refrigerant to the evaporator elements for vaporization therein at substantially equal pressures, means for controlling said refrigerant supply means in accordance with the temperatures of the evaporator elements, a fan for translating air in said second chamber in heat transfer relation with the evaporator elements therein, and means responsive to the temperature of the air in 45 said second chamber for controlling the operation of the fan; said first-mentioned temperature responsive means being so disposed that it is affected by the temperature of the air translated by the fan.

7. In refrigerating apparatus, the combination of a structure having relatively high and low temperature chambers therein, first and second evaporators disposed for cooling the chambers, a conduit connecting the evaporators and extending into both chambers, means for circulating refrigerant through the evaporators, means responsive to the temperature of the conduit and disposed within the higher temperature chamber, said temperature responsive means being effective for controlling the refrigerant circulating means, 60 a fan for circulating air within the higher temperature chamber in heat exchanging relation with the evaporator therein, means responsive to the temperature of the air in the high temperature chamber for controlling said fan, and 65 means for rendering the fan inactive in response to a predetermined abnormally high temperature of the conduit.

8. In refrigerating apparatus, the combination of a structure defining relatively high and low 70

temperature zones to be refrigerated, first and second evaporator elements for abstracting heat from said zones, respectively, first means for effecting refrigeration by the first element in response to a predetermined temperature within the high temperature zone, second means for effecting refrigeration by said second element in response to a predetermined temperature thereof,

said first temperature responsive means being effective to control refrigeration by said first evaporator element during normal operation of the apparatus, and means for rendering said first temperature responsive means ineffective in response to an abnormally high temperature of the evaporator elements.
